UNITED STATES PATENT OFFICE

CLARENCE R. DAVIS, OF DETROIT, MICHIGAN

COSTUMER

Application filed November 7, 1927. Serial No. 231,576.

My invention relates to an improvement in costumers shown in the accompanying drawings and more particularly described in the following specification and claim.

5 The primary object of this invention is to provide a costumer which may be placed in the corner of a room, or adjacent to a wall and which is adapted to support a number of garment hangers suspended from an out-standing arm projecting from a post in such a manner that the garments may not interfere with the hats hung upon a plurality of arms located above the garment supporting arm on each side of the latter.

10 A further object of the invention is to provide means for supporting the post of the costumer extending a relatively greater distance from the post on the side beneath the projecting arm,—from which the coat hangers are suspended,—than on the opposite side of the post that it may not tip over due to the weight of the clothing suspended from the arm above.

15 A further object of the invention is to provide means for supporting several umbrellas so that when wet they may not come into contact with the garments suspended from the projecting arm, the arrangement being such that the umbrellas may be readily removed from the rack or replaced without interfering with the clothing suspended from the arm.

20 This device is primarily designed for restaurants or other public places and is especially adapted to occupy as little room as possible while accommodating a relatively large number of hats and garments.

25 With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

30 In the drawings accompanying this specification:

35 Figure 1 is a perspective view of the cos-

tumer with its central column or post broken away in order that the several principal elements of the device may be shown relatively large upon the sheet,—an umbrella being indicated by dotted lines supported in the 55 rack.

40 Figure 2 is a vertical cross-sectional view through the base secured to a fragment of the post or column,—taken on or about line 2—2 of Figure 1.

45 Figure 3 is a similar vertical cross-sectional view at right angles to the preceding view,—taken on or about line 3—3 of Figure 1.

50 Figure 4 is a plan view of the umbrella supporting bracket with the post of the costumer in cross-section,—as viewed at about line 4—4 of Figure 1.

55 Referring now to the letters of reference placed upon the drawings:

60 A denotes a post which may be either a solid rod or tubular as preferred, mounted in a base member B secured by a set screw B¹ to the post.

65 C is a base plate preferably rectangular in form to which the base member B is attached by its integral central lug B¹, riveted to the plate.

70 D, D denote a pair of legs spaced apart of substantially U-shaped form, extending beneath the plate C,—and D¹, D¹ are similar legs bent to receive and overlap the first named legs—see Figures 2 and 3—the several legs being secured to the base plate C by screws E, E extending through the base plate 75 into the base member.

75 Attached to the top of the post A is a fitting F supporting a plurality of arms G secured thereto, having upwardly bent ends with an enlarged head G¹ to receive and support hats hung thereon.

80 Secured to the fitting F and extending therefrom above and in vertical alignment with the relatively longer outwardly projecting ends of the legs D¹, is an arm H formed with a plurality of notches H¹ on its upper face to receive the hooks of coat or other garment hangers I, suspended therefrom.

85 It will be apparent that the object of extending the legs D¹, D¹ a relatively greater 90

95 100

distance from the post on the side from which the arm H projects, than they do on the other side of the post is to insure the device against tipping from the weight of the garments carried by the arm—and also that the several legs D and D¹ are preferably formed with a footpiece d to provide a relatively broad support for the costumer.

J is an umbrella supporting bracket arm secured to the post A formed with a projecting spider frame J¹ with openings through the latter to receive the handles of umbrellas K, the spider frame being so constructed that hooks J² are provided which serve to confine the handle of the umbrella that it may not fall from the bracket. The end of the umbrella is adapted to extend into a removable pan L located below the base plate that moisture from the umbrella may drip therein.

Having thus described my invention what I claim is:

A costumer comprising a pair of spaced relatively long legs, a pair of spaced relatively short legs disposed transversely of the long legs, the point of intersection being midway between the ends of the short legs and at a point nearer one end of the long legs than the other, both sets of legs having intermediate portions elevated with relation to their end portions, a post mounted upon the legs at a point over the spaces between the members of both pairs of legs and a support carried by the post at a point above the legs.

In testimony whereof, I sign this specification.

CLARENCE R. DAVIS.
